MACHINE FOR FORMING HEEL SEATS

Edward F. Small, Newton, and Edward H. Bastable, Cambridge, Mass., assignors to Compo Shoe Machinery Corporation, Boston, Mass., a corporation of Delaware

Application September 16, 1952, Serial No. 309,772

5 Claims. (Cl. 12—31.5)

1

This invention relates to a machine for forming a heel seat of the type having a beveled margin merging with beveled shoulder portions extending inwardly beyond the breast line of the heel.

The desirability of providing a heel seat of the above type is well recognized in the art and numerous attempts have been made with more or less success to provide a machine for producing such a heel seat. However, such attempts have not proved entirely satisfactory in that the machines were either incapable of producing the desired bevel, or were expensive and inefficient and/or their operation required the use of a relatively expensive press.

The principal object of the present invention is to provide a compact, efficient and reliable machine for forming a heel seat of the above type, which machine can be manufactured and maintained at a fraction of the overall cost of prior machines.

Further objects relate to various features of construction and will be apparent from a consideration of the following description and the accompanying drawings which illustrate what is now considered the preferred embodiment of the invention.

In the drawings:

Fig. 1 is a side elevation, with parts broken away and shown in section, of a heel seat forming machine constructed in accordance with the present invention;

Fig. 2 is an enlarged top plan view, with parts broken away and shown in section, of the machine shown in Fig. 1;

Fig. 3 is an enlarged section substantially on the line 3—3 of Fig. 2;

Fig. 4 is a view similar to Fig. 3, but showing the knife and presser arms in advanced position;

Fig. 5 is a section on the line 5—5 of Fig. 3; Fig. 6 is a section on the line 6—6 of Fig. 4; Fig. 7 is a section approximately on the line 7—7 of Fig. 1;

Fig. 8 is an exploded view of the matrix;

Fig. 9 is a sectional isometric view of the knife carrier and certain associated parts;

Fig. 10 is a plan view showing a heel seat formed by the machine herein shown; and

Fig. 11 is an edge view of the sole shown in Fig. 10.

The machine herein shown comprises a base 1 having an upstanding column 2, the upper end of which supports a frame-like structure including spaced forwardly extending webs 4 and

2

5 (Figs. 1, 2 and 7) which adjoin correspondingly rearwardly extending webs 5 and 7, the column 2 including a removable section 8 or the like permitting access to its interior. The webs 6 and 7 are integral with a bracket 9 which extends rearwardly, as shown in Fig. 1, to provide a support for parts hereinafter described. Between the forwardly and rearwardly extending webs is a vertically extending cylinder 10, the rear portion 10 of which is provided with an opening 12 (Fig. 1), and surrounding the webs 4—7 is a shallow housing or casing 15, the top of which is formed with an opening 16 to permit access to certain parts hereinafter described.

15 Extending across the top of webs 4—7 is a bridge plate 18 (Figs. 1 and 2) formed with a central bore aligned with the cylinder 10 and disposed against the undersurface of the plate 18 is a matrix 20 (Figs. 4—6 and 8) which comprises 20 a U-shaped member 21 (Fig. 8) conforming in size and shape to the contour of the heel seat to be formed and surrounding a central recess or cavity 22. The ends of the member 21 adjoin a pivotal member 24 formed with parts 25 which provide upwardly inclined extensions or relief areas 26 and 28 (Figs. 4, 6 and 8), the inclination of which determines the angle of the bevel at the opposite lateral portion of the heel area inwardly of the breast line. Fitting within the central opening of the plate 18 is a flanged sleeve 30 (Figs. 1 and 3) which receives a piston rod 32, the lower end of which carries a stripper 34 normally disposed within the confines of cavity 22. The lower face of the stripper 34 is dished, as shown in Fig. 4, so as to provide a rounded end portion for the cavity or recess 22. The upper end of the piston rod 32 carries a piston 36 slidable within cylinder 38 mounted on the flanged upper end of the sleeve 30 as 30 shown in Fig. 1. A closure plate 40 seals the upper end of the cylinder 38 and is formed with an opening communicating with a low pressure fluid pressure line 42 (Fig. 2), the assemblage providing the equivalent of a spring for yieldingly holding the stripper 34 in lowermost or stripping position. Screws 43 (Fig. 2) extend through the closure plate 40 into the bridge plate 18 to hold the assemblage together.

45 Since the member 24 is, in effect, pivotally connected to the member 21, its angular position may be adjusted so as to vary the angle of bevel and to this end the bridge plate 18 is formed with vertically extending openings to receive a plurality of small compression springs 46 which act on the inner edge of member 24, as shown more

clearly in Fig. 3, and a set screw 45, extending through bridge plate 18, engages the upper face of member 24 so as to hold it in the desired position of adjustment.

Mounted within the cylinder 10 is a reciprocating plunger 52, the central portion of which is machined to provide a rack 54 meshing with a gear 55 keyed to a transversely extending shaft 56, the opposite ends of which are journaled in bosses 58 and 60 (Figs. 2 and 7) integral with the webs 6 and 7. The shaft 56 is also keyed to a rearwardly extending arm 64 (Figs. 1 and 7), the outer end of which is connected by a link 65 to a treadle 66 pivotally mounted at 68 to the rear part of the base 1. One end of a retracting spring 70 is pinned to the interior of the column 2 and its opposite end is secured to a collar 72 carried by the link 65, the spring 70 being effective normally to hold the plunger 52 in retracted position, as shown in Fig. 1.

Mounted on the upper part of the plunger 52 is a depressor 74, the head or upper end 75 of which is of generally rectangular shape so as to enter the cavity 22, as illustrated in Figs. 5 and 6, it being understood that the pressure of the depressor 74 greatly exceeds that of the stripper 34 so that the latter is readily retracted. The front of the head is serrated and its rear face is formed with a downward bevel, as shown in Figs. 3 and 4, to conform to the curvature of the rear wall of the stripper 34. The serrated head 75 cooperates with the stripper to hold a sole in position, and the rear wall of the depressor is formed with a notch 77 (Figs. 3 and 4), the utility of which is hereinafter pointed out.

A shaft 76 (Figs. 1 and 3), between the forward ends of the webs 4 and 5, is carried by a rearwardly extending arm 78 formed adjacent to its free end with a depending portion 80 and the free end of this arm is bifurcated to provide spaced dogs 81 (Figs. 1 and 3-5) engageable with the lower flanged end of the depressor 74 so that elevation of the plunger 52 rocks the arm 78 in a counter-clockwise direction. The lower part of the depending portion 80 is formed with an elongate transversely extending sleeve 82 (Figs. 3 and 4) parallel to the shaft 76, and mounted within the sleeve 82 is a shaft 84, the opposite ends of which project laterally so as to support a pair of cooperating pressers and associated parts designated generally by the numeral 85.

Each presser comprises a T-shaped member 86 (Figs. 3 and 4) having a forwardly projecting arm 87 and an upstanding arm 88, the outer end of the arm 87 carrying a transversely extending shaft 90 and the upper end of the arm 88 supports one end of a shaft 92, as shown more clearly in Figs. 3, 4 and 7. Inwardly of each T-shaped member 86 is a rocker arm 94 mounted on shaft 92 in approximate parallel relation to the adjacent arm 88 and the upper end of the rocker arm 94 carries a self-aligning arm 95 extending rearwardly on each side of the depressor 74 (Figs. 3-6). Guide disks 93 (Fig. 7) are provided to fix the position of the rocker arms 94 relative to the matrix 21. The end of each arm 95 is forked to receive a roller 96 rotatable on a stub shaft 98. The outer or front face of rocker arm 94 is provided with a bumper pad 99 engageable with a stop hereinafter described.

Carried by shaft 90 and in alignment with the associated rocker arm 94 is a block 100 (Fig. 3) and the outer end portion of a spindle 101 pro-

jects through the block 100 and shaft 90, the inner end of the spindle being pivoted to the lower end of rocker arm 94. The outer end of the spindle 101 extends beyond the block 100 and carries lock nuts 102. Circumposed about the spindle is a compression spring 104, one end of which acts on an adjustable bushing 105 and the opposite end acts against the lower end of rocker arm 94 so as yieldingly to oppose clockwise rocking movement of the arm 95 (Fig. 3) when the arm 86 is swung counter-clockwise (Fig. 4) in the manner hereinafter described. By adjusting the nuts 102 the angular position of arm 95 and the pressure to be exerted by the associated roll 96 may be varied.

The arm 78, outwardly of the depending part 80, is provided with a pair of transversely extending shoulders 106 (Figs. 1-3 and 7) each of which is provided with an adjustable stop 108 constructed and arranged to limit the counter-clockwise rocking movement of rocker arm 86 (compare Figs. 3 and 4). On each side of the depressor 74 between arms 88 and 95 is a slotted link 110 (Figs. 3, 4 and 7) through which the shaft 92 extends, the construction and arrangement of parts being such that the links 110 travel forwardly a predetermined distance before the inner end of their slotted portions engage the shaft 92 to swing the rocker arms counter-clockwise against the stops 108, as will be noted by comparing Figs. 3 and 4.

Mounted on top of the housing 15 is a horizontal work rest 115, the central inner part of which is recessed so as to accommodate the matrix 20 (Figs. 1, 3 and 4). The front and side of the work rest carry adjustable gauges designated by the numerals 117 and 118 (Fig. 2) which are designed properly to position right and left soles of a given length. Inasmuch as these gauges are of conventional design and as their construction and mode of operation is apparent from the drawings, a further description is unnecessary.

It will be noted that with the construction and arrangement of parts thus far described, a sole S may be positioned on the work rest with its heel area H between the matrix and the depressor as shown by the broken lines of Fig. 2; and when the treadle 66 is depressed, the plunger 52 elevates the depressor 74 so as to force the central heel area into the cavity 22 of the matrix, thus leaving the margin of the heel area extending outwardly at an angle to the marginal portion of the matrix, and simultaneously the arm 78 is rocked counter-clockwise by the engagement of the base of the depressor 74 with the dogs 81, as shown in Fig. 3; and when the rocker arm 94 is swung forwardly, as hereinafter explained, the arms 95 with rollers 96 swing forwardly and upwardly against the opposite lateral areas at and adjacent to the breast line of the heel seat to hold these parts against the inclined extensions 26 and 28, as illustrated in Figs. 5 and 6.

The inner walls of webs 6 and 7 adjacent to their upper edges are formed with guides 119 (Fig. 9) which slidably support a knife carrier 120 having forwardly extending arms 121 and 122, each end of which carries a stop 124. Secured to the underside of the carrier 120 between its arms is an interlock 128, the free end of which is engageable with the notch portion 77, as shown more clearly in Fig. 4. The carrier 120 is connected to a transversely extending

yoke member 130 by a stud 131, as shown in Figs. 1 and 7.

A U-shaped knife (Fig. 9) consisting of three sections, i. e., a central section 132 and a pair of outer sections 133 and 134, is adjustably mounted on the carrier 120 by the several pairs of set screws 135 extending through the slots in clamping plates 136 (Fig. 2) and the tail ends of the knives. The parts cooperate with set screws 137 (carried by a plate 137^a which is secured to the end wall of the carrier 120), guide plates 138 and the stops 124 to hold the knife sections 132—134 rigidly together, as illustrated in Figs. 2 and 9. The distance between the cutting edge of section 132 and those of sections 133 and 134 is such that the latter completes the trimming operation along the sides and breast line of the heel seat before the section 132 completes the trimming of the rear part of the heel. Surrounding the depressor is a chute 139 (Fig. 1) for conducting the trimmings to the exterior of the machine.

The movement of the knives and rocker arm 94 from retracted position (Figs. 1 and 3) to advanced position (Figs. 4 and 6) may be effected in any suitable manner, here shown as a mechanism comprising a fluid pressure cylinder 140, one end of which is secured to the bracket 9. Within the cylinder 140 is a piston having a piston rod 142, the end of which is pivotally connected with the yoke 130 by a clevis 143 through which the stud 131 extends (Figs. 1 and 7). The opposite ends of the yoke 130 are connected with the inner ends of links 110 by clevises 144 (Fig. 7) and since the knife carrier is connected to yoke 130 by the stud 131 both the links and knife advance simultaneously when fluid pressure is admitted to the cylinder 140.

The control of the fluid pressure is effected by a three-way valve 146 (Figs. 1 and 2) connected to a suitable source of fluid pressure such as compressed air. The valve 146 is provided with an operating lever 147 (Figs. 1 and 2) which in one position admits air to one end of the cylinder 140 and at the same time vents the opposite end of the cylinder; and in the second position the valve 146 admits pressure to said opposite end while venting the other end of the cylinder.

The operating lever 147 is pivotally connected to an extension 148 of the treadle 66 by a link 150, the construction and arrangement of parts being such that the treadle 66 when depressed is first effective to elevate the depressor and then operate the valve lever 147 to admit air to the cylinder 140. When the treadle is released the spring 70 retracts so that the operating lever 147 is moved to the second or normal position, wherein compressed air is admitted to the opposite end of the cylinder to retract the parts.

A summary of the operation of the machine is as follows:

Assuming that the depressor, knife, etc., are in retracted position (Fig. 1) and that the gauges 117 and 118 have been properly adjusted for the soles S to be operated on, a sole is then positioned on the work rest with its heel area between the matrix 20 and depressor 74 as indicated by the dotted lines of Fig. 2. Initial depression of the treadle 66 first elevates the depressor 74 so as to press or deform the central area of the heel into the matrix, leaving the peripheral portions to be trimmed projecting outwardly as shown in Fig. 3; simultaneously the arm 78 is elevated so that the rolls 96 engage

the undersurface of the sole forwardly of the breast line of the heel and hold the projecting portions against the flat marginal portions 21 of the matrix, as shown in Fig. 5. Continued downward movement of the treadle operates the three-way valve 146 to admit air to the cylinder 140 thus advancing the knife carrier 120, interlock 128 and the links 110. As the parts advance the interlock 128 approaches the notch 77 (Fig. 3) and the links 110 contact the shaft 92 to swing the rolls 96 forwardly and upwardly; and simultaneously the knife sections 133 and 134 contact the projecting edges at the side of the heel area to start the trimming operation. As the rolls 96 travel forwardly and upwardly they press the untrimmed lateral margins against the inclined extensions 26 and 28 (see Figs. 5 and 6) thus distorting the heel area at and adjacent to the breast line so that the knife sections 133 and 134 in advancing form a bevel cut, as shown more clearly in Fig. 4, after which the central knife section 132 comes into operation to trim the rear heel area, and simultaneously the interlock engages the notched part of the depressor 74, as shown in Fig. 4. The trimmed marginal portions of the heel area drop down into the chute 139 which conducts them away.

When the treadle 66 is released, the lever 147 operates to exhaust the cylinder and admit compressed air to its opposite end, whereupon the knife carrier, interlock, rocker arms 94 and associated parts are moved back to retracted position and the piston 38 operates the stripper plate 34 to push the heel seat out of the cavity 22 of the matrix. The sole is then manually removed and the operation is repeated.

The trimmed sole, as shown in Figs. 10 and 11, is thus formed with a heel seat H having beveled margins 155 merging with the beveled shoulder portions 156 which extend inwardly beyond the breast line 158.

While we have shown and described one desirable embodiment of the invention, it is to be understood that this disclosure is for the purpose of illustration and that various changes and modifications may be made without departing from the spirit and scope of the invention as set forth in the appended claims.

We claim:

1. A heel seat forming machine comprising matrix and depressor members relatively movable toward and away from each other and between which the heel portion of a sole is received, the matrix member having a central cavity surrounded by a generally U-shaped marginal portion corresponding to the periphery of the heel seat area, the open ends of said U-shaped marginal portion having extensions outwardly inclined from a line corresponding to the breast line of the heel seat, means for relatively moving said matrix and depressor members toward each other so that the central heel area of a sole is pressed into said cavity with its margin projecting at an angle to said U-shaped marginal portion, a pair of spaced presser members pivotally mounted to swing from a retracted position to an advanced position contiguous to the inclined extensions so as to bend and hold opposite lateral portions of the heel area inwardly of its breast line against said extensions, a U-shaped knife movable in a path contiguous to said U-shaped marginal portion, and means operable when said depressor is moved against said matrix for advancing said knife and swinging said presser

members toward said extensions so as to trim said projecting margin of the heel area and said opposite lateral portions thereby to form a heel seat having beveled margins merging with beveled shoulder portions extending inwardly beyond the breast line of said heel portion.

2. A heel seat forming machine comprising a fixed matrix, a depressor movable toward and away from said matrix and between which the heel portion of a sole is received, the matrix having a central cavity surrounded by a generally U-shaped marginal portion corresponding to the periphery of the heel seat area, the open ends of said U-shaped marginal portion having extensions outwardly inclined from a line corresponding to the breast line of the heel seat, a pair of spaced presser members pivotally mounted to swing from a retracted position to an advanced position contiguous to the inclined extensions so as to bend and hold opposite lateral portions of the heel area inwardly of its breast line against said extensions, a U-shaped knife movable in a path contiguous to said U-shaped marginal portion, and actuating means for moving said depressor toward said matrix so as to press the central heel area of a sole into said cavity with its margin projecting outwardly at an angle and then advancing said knife along said path and swinging said presser members toward said extensions, thereby to trim said projecting margin of the heel area and said opposite lateral portions and form a heel seat having beveled margins merging with beveled shoulder portions extending inwardly beyond the breast line of said heel portion.

3. A heel seat forming machine comprising a frame, a matrix carried by said frame, said matrix having a central cavity surrounded by a generally U-shaped marginal portion corresponding to the periphery of the heel seat area, the open ends of said U-shaped marginal portion having extensions outwardly inclined from a line corresponding to the breast line of the heel seat, a work rest for supporting a sole so that its heel area is juxtaposed to said matrix, a depressor mounted on said frame and movable from a retracted position to an advanced position wherein it presses the central heel area of said sole into said cavity with the margin of said heel area projecting outwardly at an angle to said U-shaped marginal portion, guideways on the frame on each side of said matrix adjacent to said U-shaped marginal portion, presser means mounted on said frame and movable from a retracted position first to an intermediate position wherein it contacts the outwardly projecting margin of said heel area and then to an advanced position wherein it bends and holds the opposite lateral portions of the heel seat area inwardly of its breast line against said extensions, a knife mounted on said guideways and movable from a retracted position to an advanced position to trim said projecting margin of the heel area and said opposite lateral portions, and means for advancing said depressor and simultaneously moving said presser means to intermediate position and thereafter advancing said knife and moving said presser means to advanced position thereby to form a heel seat having beveled margins merging with beveled shoulder portions extending inwardly beyond the breast line of said heel area.

4. A heel seat forming machine comprising a frame, a matrix carried by said frame, said matrix having a central cavity surrounded by a generally U-shaped marginal portion corre-

sponding to the periphery of the heel seat area, the open ends of said U-shaped marginal portion having extensions outwardly inclined from a line corresponding to the breast line of the heel seat, a work rest for supporting a sole so that its heel area is juxtaposed to said matrix, a depressor mounted on said frame and movable from a retracted position to an advanced position wherein it presses the central heel area of said sole into said cavity with the margin of said heel area projecting outwardly at an angle to said U-shaped marginal portion, guideways on the frame on each side of said matrix adjacent to said U-shaped marginal portion, presser means mounted on said frame and movable from a retracted position first to an intermediate position wherein it contacts the outwardly projecting margin of said heel area and then to an advanced position wherein it bends and holds the opposite lateral portions of the heel seat area inwardly of its breast line against said extensions, a knife mounted on said guideways and movable from a retracted position to an advanced position to trim said projecting margin of the heel area and said opposite lateral portions, an operating lever movable from inactive to active position, and means interconnecting said operating lever, depressor, knife and presser means and effective when said lever is moved to active position first to advance said depressor and move said presser means to intermediate position, then advance said knife and move said presser means to advanced positions in response to the approach of said knife thereby to form a heel seat having beveled margins merging with beveled shoulder portions extending inwardly beyond the breast line of said heel area.

5. A heel seat forming machine comprising a frame, a matrix carried by said frame, said matrix having a central cavity surrounded by a generally U-shaped marginal portion corresponding to the periphery of the heel seat area, the open ends of said U-shaped marginal portion having extensions outwardly inclined from a line corresponding to the breast line of the heel area which is juxtaposed to said matrix, a depressor slidably mounted on said frame and movable from a retracted position to an advanced position wherein it presses the central heel area of said sole into said cavity with the margin of said heel area projecting outwardly at an angle to said U-shaped marginal portion, guideways on the frame on each side of said matrix adjacent to said U-shaped marginal portion, a pair of spaced presser arms pivotally mounted to swing from a retracted position first to an intermediate position wherein their free ends contact the outwardly projecting margin of the heel area and then to advanced position wherein their free ends are contiguous to said extensions so as to bend and hold opposite lateral portions of the heel area inwardly of its breast line against said extensions, a U-shaped knife mounted on said guideways and movable from a retracted position to an advanced position to trim said projecting margin of said heel area and said opposite lateral portions, a treadle pivotally mounted so as to swing from an inactive to an active position, and interconnections between said treadle, depressor, knife and presser arms operative in response to movement of said treadle to active position first to advance said depressor and simultaneously swing said presser arms to intermediate position, then advance said knife and

finally move said presser arms to advanced position in response to the approach of said knife, thereby to form a heel seat having beveled margins merging with beveled shoulder portions extending inwardly beyond the breast line of said heel area. 5
